UNITED STATES PATENT OFFICE

2,356,537

FLANGE HOLD-IN DEVICE FOR WRAPPING MACHINES

Oscar Sandberg, Defiance, Ohio, assignor to Lynch Manufacturing Corporation, Defiance, Ohio, a corporation of Ohio

Application December 16, 1943, Serial No. 514,471

7 Claims. (Cl. 93—2)

My present invention relates to a hold-in device for the flange of an article receiving boat in a wrapping machine which wraps a wrapper around the boat and article.

One object of the invention is to provide a hold-in device of simple construction involving a minimum of parts for its operation in timed relation to other mechanism of the wrapping machine.

Another object is to provide a hold-in device which is movable to two different positions; one wherein it permits boats with articles therein to pass freely beneath it, and another where it swings in back of the boat for holding a flange of the boat from assuming an improper position and instead, guiding it into a folding way.

A further object is to provide a stop plate cooperating therewith so that both flanges of a channel shaped article holding boat are properly guided into the folding way without danger of springing outwardly before entering the way and jamming the machine, or at least spoiling the package.

With these and other objects in view, the invention comprises the combination of elements and the arrangement of parts which are so combined with each other as to cooperate in the performance of the functions and accomplishment of the results herein contemplated. The invention comprises in one of its adaptations the species or preferred form illustrated in the accompanying drawing, wherein—

Figure 1 is a side elevation of a portion of a wrapping machine, such as shown in my Patent No. 2,283,097, with my present flange hold-in device added thereto.

Figure 2 is an enlarged view of the hold-in element shown in section and showing the normal position thereof while a pocket of a conveyor passes beneath it, such pocket being illustrated with a channel-shaped article holding boat therein and an article such as a candy bar in the boat.

Figure 3 is a similar view showing the pocket further advanced and the hold-in element being swung from the position in Figure 2 to another position, it being intermediate the two positions.

Figure 4 is a similar view showing the hold-in element in said another position when the pocket is in position for elevation of the boat and article into a folding way; and

Figure 5 is a sectional view on the line 5—5 of Figure 4.

On the accompanying drawing I have used the

reference character F to indicate a wrapping machine frame, and T a wrapper supporting table. Above the table T a folding way F is mounted, as shown in my prior patent, and spaced above the table so that a wrapper can be positioned between the table and the folding way. The wrapper is not shown in the drawing, however.

The wrapping machine includes a pocket conveyor, 10—12, 10 being the chain thereof and 12 the pockets thereof. The pocket conveyor is driven by a chain 13 from a Geneva movement including a star wheel 14 and a cooperating disc 15, arm 16, and roller 17. This type of drive, upon rotation of a shaft 18 on which the elements 15, 16 and 17 are mounted, results in intermittent movement of the star wheel 14 and consequently the pocket conveyor 10—12. The stopped position of each pocket in relation to a folding way FW is shown in Figure 1.

The pockets 12 are adapted to receive channel shaped cardboard boats 19, such as disclosed in my co-pending application, Serial No. 461,709, filed October 12, 1942, and the boats in turn receive articles 20, such as candy bars or pieces of candy. The boats and candy are then adapted to be wrapped in a wrapper of paper, or the like, by elevation of the boats by a vertically movable ram 21 (see Figure 1) which engages them with the bottom of a wrapper on the table T (not shown) and moves them up through the folding way FW for draping the wrapper about the boat and article, the downhanging ends then being folded in under the article, as shown in my former patent.

The boats 19 have a tendency to spring open although they are held by the sides of the pockets 12. When the ram 21 elevates a boat out of the pocket there is danger of the flanges of the boat spreading to such an extent that they engage the edges of an opening 22 in the table T or the lower end of the folding way FW and thus either jamming the machine or spoiling the package. To take care of this, the front flange of the boat is guided by a stop plate 23 depending from the table T and having therein a notch 24. The notch 24 permits passage of the conveyor pocket but portions 25 of the stop plate beyond the ends of the notch 24 engage the front flange of the boat as shown in Figure 5 to cause the flange to cooperate with the main body portion of the plate 23 which properly guides it up through the opening 22 and into the folding way.

A stationary plate of this character cannot be provided for the rear flange of the boat. However, I do provide a similar plate 23a having a

notch 24^a and end portions 25^a, which plate is movably mounted by attachment thereof to a rock shaft 26. The rock shaft 26 is journaled in suitable bearings 27 depending from the table T and is operated to two different positions, as shown in Figures 2 and 4, by an arm 28, a link 29, a bell crank 30 pivoted at 31 on the frame F, and a cam disc 33. The disc 33 has a cam groove 34 in which a roller 35 of the bell crank 30 travels for timing the movements of the hold-in element 23^a with relation to the pocket conveyor 10—12.

Normally, the hold-in element 23^a assumes the position of Figure 2, but when a pocket 12 reaches a position of alignment with the folding way FW and stops in that position, the flange 23^a is in the position of Figure 4 and remains there until the ram 21 has raised and then starts to lower. The element 23^a is then moved back to the position of Figure 2 so that the next boat and article coming to wrapping position does not strike it, but instead passes under it, as shown in Figure 2.

My hold-in device is substantially simple in construction and effectively retains the boat 19 against any spreading to an inoperative position. Its flanges are guided into the folding way FW without buckling or being otherwise damaged.

Some changes may be made in the construction and arrangement of the parts of my flange hold-in device for wrapping machines without departing from the real spirit and purpose of my invention, and it is my intention to cover by my claims any modified forms of structure or use of mechanical equivalents which may be reasonably included within their scope without sacrificing any of the advantages thereof.

I claim as my invention:

1. A flange hold-in device for wrapping machines, comprising a hold-in element movably mounted adjacent an intermittently operable conveyor of a wrapping machine which conveys articles in channel shaped boats to a position aligned with a folding way, said hold-in element in one position permitting the boat and article to pass therebeneath, and in another position being behind the boat to guide the rear flange thereof into the folding way, and a stop plate adjacent the front flange of the boat, said stop plate having a notch for the conveyor to pass through with the boat extending beyond the sides of the conveyor for engagement of said front flange beyond the ends of said notch with said stop plate, said hold-in element being provided with a notch to clear the conveyor with portions of the element beyond the ends of the notch assuming a position behind the rear boat flange.

2. A flange hold-in device for wrapping machines, comprising a hold-in element movably mounted adjacent an intermittently operable conveyor of a wrapping machine which conveys articles in channel shaped boats to a position aligned with a folding way, said hold-in element in one position permitting the boat and article to pass therebeneath, and in another position being behind the boat to guide a flange thereof into the folding way.

3. A flange hold-in device for wrapping ma-

chines, comprising a hold-in element movably mounted adjacent a conveyor of a wrapping machine which conveys articles in channel shaped boats to a position aligned with a folding way, said hold-in element in one position permitting the boat and article to pass therebeneath, and in another position being behind the boat to guide the rear flange thereof into the folding way, and a stop plate in front of the boat to guide the front boat flange into the folding way.

4. In a flange hold-in device for wrapping machines, a rock shaft located between an intermittently operable conveyor and a wrapper carrying table of a wrapping machine in which the conveyor conveys articles in channel shaped boats to a folding way mounted above the wrapper carrying table, means timed with the wrapping machine mechanism that intermittently operates said conveyor for rocking said rock shaft, and a hold-in plate carried by said rock shaft and in one position of the shaft being above a boat and an article in said conveyor and in another position of the shaft being back of a flange of the boat to hold said flange in position for entering the folding way.

5. In a flange hold-in device for wrapping machines, a rock shaft located above an intermittently operable conveyor of a wrapping machine which conveys articles in channel shaped boats to a folding way mounted above a wrapper carrying table of the machine, means timed with the wrapping machine mechanism for rocking said rock shaft, a hold-in plate carried by said rock shaft and in one position of the shaft being above a boat and an article in said conveyor and in another position of the shaft being back of a flange of the boat to hold said flange in position for entering the folding way, and a stop plate stationary on said table for the other flange of the boat to hold it in position for entering the folding way.

6. In a flange hold-in device for wrapping machines, a rock shaft located above an intermittently operable conveyor of a wrapping machine which conveys articles in channel shaped boats to a folding way mounted above a wrapper carrying table of the machine, means timed with the wrapping machine mechanism for rocking said rock shaft, and a hold-in plate carried by said rock shaft and in one position of the shaft being above a boat and an article in said conveyor and in another position of the shaft being back of a flange of the boat to hold said flange in position for entering the folding way.

7. In a flange hold-in device of the character disclosed, a rock shaft located adjacent an intermittently operable conveyor of a wrapping machine which conveys articles in channel shaped boats to a folding way, means timed with the wrapping machine mechanism for rocking said rock shaft, and a hold-in element carried by said rock shaft and in one position of the shaft being above a boat and an article in said conveyor and in another position of the shaft being back of a flange of the boat.

OSCAR SANDBERG.
